UNITED STATES PATENT OFFICE.

LOUIS N. VINCENT, OF SEATTLE, WASHINGTON.

FLANGE LUBRICATOR OR OILER.

Original application filed September 30, 1921, Serial No. 563,282. Divided and this application filed May 25, 1922. Serial No. 563,565.

To all whom it may concern:

Be it known that I, LOUIS N. VINCENT, a citizen of the United States, residing at Seattle, in the county of King, State of Washington, have invented certain new and useful Improvements in Flange Lubricators or Oilers; and I do hereby declare the following to be a full, clear, and exact description of the invention, such as will enable others skilled in the art to which it pertains to make and use the same.

My invention relates to improvements in flange lubricators and more particularly to flange lubricators for use in lubricating or oiling the flanges of wheels of steam, electric and other cars and locomotives.

This application is a division of an application for patent filed by me on the 30th day of September, 1921, Serial No. 504,282, for flange oiler or lubricator.

The invention consists in the several features and in the construction, combination and arrangement of such features as more fully hereinafter described and claimed.

25 The object of the invention is to thoroughly lubricate the flanges of wheels, especially when the wheels are travelling on the curved portions of a track, as very little lubrication is required on the flanges when on a straight track.

A further object is to provide a flange lubricator which is automatically operated and caused to feed lubricant to the flanges of wheels by means of the lateral or sidewise movement or play of the truck frame or engine frame from side to side and also the lateral play or movement from side to side of the wheels between the rails during their travel on the track.

40 A further object is to provide a flange lubricator which is automatically operated and caused to supply or feed grease from the grease cups to the flange lubricating means by means of the lateral or sidewise movement or play of the truck frame from side to side and also the lateral play or movement from side to side of the wheels between the rails during their travel on the track.

50 A further object is to dispense with all springs, weights or other devices for holding the nozzles against the flanges of the wheels, which is a great advantage, as all such devices are liable to get out of order.

A further object is to provide a flange lubricator which operates automatically and requires no attention or care except the keeping of the lubricant cups well supplied with lubricant.

A further object is to provide a flange lubricator which automatically adjusts itself to the movement of the wheels in such manner that its position with relation to the wheels is always the same.

A still further object is to provide a flange lubricator which is simple, inexpensive and durable in construction and easy and effective in operation.

Referring to the drawings:

Fig. 1, is a front view in elevation.

Fig. 2, is a sectional view, partly in elevation.

Fig. 3, is a top plan view of the means for adjusting the connecting rod of the rocker arms.

In the drawings, in which similar reference characters denote similar parts throughout the several views, 1 represents the flange lubricator which comprises two lubricant containers or grease cups 2 and 3 connected or coupled together by means of a tube or pipe 4, which is adapted to be secured and supported by a suitable bracket or brackets, not shown, on a car or locomotive.

The lubricant containers 2 and 3 are each made, preferably, in three parts, 5, 6 and 7 connected together by means of a short vertical pipe 8, and the upper part 5 of each being provided with a screw cap or other closure 9.

A slideable or reciprocatory hollow plunger 10 is mounted in a bushing 11, in the lower part 7 of each lubricant container, which is provided with a nozzle 12 having 95 a suitable anti-friction roller or wheel 13 in its outer end, and a sleeve 14 embraces the hollow plunger 10.

Rockers arms or levers 15 are provided each pivotally mounted on a pin 17 extending through a bracket 18 which depends from a hollow projection 19 extending laterally from the part 6 of the lubricant container.

The upper ends of the rocker arms 15 are 105 pivotally connected by means of a pin 20 to a connecting or coupling rod 21, which extends through pipe 4, while the lower ends

of the rocker arms are loosely mounted on a pin 22 projecting laterally from the sleeve 14.

Although I have described the nozzles as being made of flexible rubber, they may be made of metal covered with rubber or any other suitable material desired.

In order to provide means whereby the nozzles may be adjusted, with relation to the wheels being lubricated, the connecting rod 21 is screwthreaded at each end, as at 23 see Figure 3, into a block 24, and by screwing the same in or out of the block the nozzles will be moved respectively toward 15 or away from the wheels.

In use the flange lubricator is placed over and straddles the flanges of a pair of wheels and is properly adjusted and then held in place by means of a suitable bracket carried by the car or locomotive in such position that the ends of the nozzles abut against the sides of the flanges of the wheels, the lubricant cups having been filled with lubricant, the reciprocating movement of the 25 rocker arms, produced by the lateral or sidewise movement or play of the engine or truck frame from side to side, also the lateral play or movement from side to side of the wheels, causes the hollow plungers or 30 pipes to be reciprocated or moved back and forth in the lower portions of the lubricant receptacles or containers, and each inward movement of the plungers or pipes causes the lubricant to be continuously forced 35 through the hollow plungers and out through the ends of the nozzles onto the flanges of the wheels, while the outward movement of the plungers allows the lubricant to be fed or moved downward in the 40 lubricant containers in sufficient quantity to take the place of the lubricant which has been used, and by the continued lateral play of the engine or truck frame and wheels the plungers are caused to reciprocate or slide 45 back and forth and the extent of movement of the plungers is regulated by the extent of lateral play of the wheels.

The continuous turning or rotating of the wheels causes the lubricant fed to the flanges 50 to be spread all around the flanges of the wheels.

The constant jarring of the car or locomotive results in the continual packing of the lubricant or grease in the containers.

As the lubrication of the flanges of the wheels is required mostly on curves, when the wheels take the curve it will cause the flange lubricator to force the lubricant or grease onto the flanges of the wheels and in 55 turning the curve either to the right or to the left, as the case may be, the side of the curved track where the lubricant is needed will be the side lubricated, and when running on a straight track there will be sufficient lateral motion or play of the engine 60

or truck frame and wheels to cause the lubricator to supply more or less lubricant to the flanges.

I do not wish to be understood as limiting myself to the specific details of construction and arrangement as herein described and illustrated, as it is manifest that variations and modifications may be made in the features of construction and arrangement in the adaptation of the device to various conditions of use without departing from the spirit and scope of my invention and improvements. I therefore reserve the right to all such variations and modifications as properly fall within the scope of my invention and the terms of the following claims.

What I claim is:

1. In a flange lubricator for wheels, lubricant receptacles, means for connecting said receptacles, slidable lubricant feeding means, means pivoted to each of said receptacles for operating said lubricant feeding means and means for inter-connecting said pivoted means, said lubricant feeding means adapted to contact with and be operated by the flange of a wheel.

2. In a flange lubricator for wheels, lubricant receptacles, hollow plungers or pipes slidable in said receptacles, and rocker arms pivoted to said receptacles and connected to said hollow plungers or pipes, each of said hollow plungers adapted to contact with the flanges of a wheel and be reciprocated by the lateral movement or play of the engine or truck frame and wheels.

3. In a flange lubricator for wheels, lubricant receptacles, each of said receptacles having a hollow plunger or pipe mounted and slidable therein and means pivoted to said receptacles and connected to said hollow plungers or pipes, said pivoted means and plungers or pipes being adapted to be reciprocated by the lateral movement or play of the engine or truck frame and wheels.

4. In a flange lubricator for wheels, lubricant receptacles, hollow plungers or pipes slidable in said receptacles, pivoted rocker arms connected to said hollow plungers and a rod for connecting said rocker arms, said hollow plungers or pipes adapted to contact with and be operated by the flange of a wheel.

5. In a flange lubricator for wheels, lubricant receptacles, hollow plungers or pipes having nozzles for delivering lubricant, rocker arms, a rod pivotally connecting the upper ends of said rocker arms and the lower ends of said rocker arms pivoted to the hollow plungers, said hollow plungers or pipes adapted to contact with and be operated by the flange of a wheel.

6. In a flange lubricator for wheels, lubricant receptacles, hollow plungers or pipes mounted and slidable in said lubricant re-

- ceptacles, brackets depending from said receptacles, rocker arms pivoted to said brackets and connected to said hollow plungers, and means for connecting said rocker arms, 5 said hollow plungers or pipes adapted to contact with and be operated by the flange of a wheel.
7. In a flange lubricator for wheels, lubricant receptacles connected by tubular means, 10 lubricant feeding means mounted and slideable in said lubricant receptacles, means pivoted to each of said receptacles and connected to said tubular means, and means for connecting said pivoted means which extends through the said tubular means of the 15 receptacle, said lubricant feeding means adapted to contact with and be operated by the flange of a wheel.
8. In a flange lubricator for wheels, lubricant receptacles connected by tubular means, 20
- hollow plungers mounted and slideable in said lubricant receptacles, brackets depending from said receptacles, rocker arms pivoted on said brackets and having a connecting rod extending through said tubular 25 means, said rocker arms and plungers adapted to be reciprocated by the lateral movement or play of truck frame and the wheels.
9. In a lubricator for wheels, lubricant receptacles, means for connecting said receptacles, slideable lubricant feeding means having a pin, means pivoted to each of said receptacles and engaging the said pin and means for connecting said pivoted means, 30 said lubricant feeding means adapted to contact with and be operated by the flange of a 35 wheel.

In testimony whereof I have affixed my signature.

LOUIS N. VINCENT.
